UNITED STATES PATENT OFFICE.

BESSIE M. CHESTER, OF LONG BEACH, CALIFORNIA.

DESIGN FOR A WOVEN-PALM-LEAF BONNET-FRAME.

49,050.

Specification for Design.

Patented May 16, 1916.

Application filed February 16, 1916. Serial No. 78,783. Term of patent 7 years.

To all whom it may concern:

Be it known that I, BESSIE M. CHESTER, a citizen of the United States, residing at Long Beach, in the county of Los Angeles and State of California, have invented a new, original, and ornamental Design for Woven-Palm-Leaf Bonnet-Frames, of which the following is a specification, reference being had to the accompanying drawing, forming a part thereof, in which—

Figure 1 is a side elevation of the bonnet frame; and Fig. 2 is a front elevation of the same.

What I claim is:

The ornamental design for a woven palm leaf bonnet frame, as shown.

BESSIE M. CHESTER.

Witnesses:

F. A. ZIEGLER,
STELLA MCKEE.
